(**) Term: **14 Years**

The ornamental design for a rear combination lamp for two-wheeled motor vehicles, as shown and described.

(21) Appl. No.: **29/203,277**

DESCRIPTION

(22) Filed: **Apr. 13, 2004**

FIG. 1 is a front view of a rear combination lamp for a two-wheeled motor vehicle.

(30) **Foreign Application Priority Data**

FIG. 2 is a rear view thereof.

Oct. 14, 2003 (JP) 2003-030236

FIG. 3 is a plan view thereof.

(51) **LOC (8) CI.** **26-06**

FIG. 4 is a bottom view thereof.

(52) **U.S. CI.** **D26/28**

FIG. 5 is a right side view thereof.

(58) **Field of Classification Search** D26/28-36; 362/459-468, 473-476, 485-487

FIG. 6 is a left side view thereof.

See application file for complete search history.

FIG. 7 is a perspective view thereof as seen from the left front side.

(56) **References Cited**

FIG. 8 is a perspective view thereof as seen from the right front side.
